Patented Jan. 11, 1921.

UNITED STATES PATENT OFFICE.

RAYMOND K. BEVIER, OF SPOKANE, WASHINGTON.

MOVABLE ADVERTISING DEVICE FOR AEROPLANES, &c.

1,365,219.

Specification of Letters Patent. Patented Jan. 11, 1921.

Application filed November 11, 1919. Serial No. 337,328.

To all whom it may concern:

Be it known that I, RAYMOND K. BEVIER, a citizen of the United States, residing at Spokane, in the county of Spokane and 5 State of Washington, have invented new and useful Improvements in Movable Advertising Devices for Aeroplanes, &c., of which the following is a specification.

This invention relates to advertising devices and particularly to aerial advertising apparatus, and has for its object to provide the combination with an airplane, of an advertising device that is rendered visible by the operation of an airplane, and further 15 more which provides for a change of the advertised subject matter while the airplane is in flight; and the invention consists of the construction, combination and details as illustrated in the accompanying drawings 20 and described and claimed hereinafter.

Figure 1 is a perspective of an airplane disclosing the advertising features.

Fig. 2 is a perspective of the airplane in an inverted position.

Fig. 3 is a top plan view of an airplane showing in detail parts of the advertising mechanism partly broken away.

Fig. 4 is an elevation of the operating mechanism for changing the position of the 30 advertising sheets.

Fig. 5 is a transverse section on line 5—5 of Fig. 3.

Fig. 6 is a transverse section on line 6—6 of Fig. 4.

35 My present invention broadly contemplates the combination with an aerial vehicle, such for instance as an airplane 2, means for effectively displaying insignia and particularly for displaying advertising material, and incorporates means for securing a 40 change of the display at will as either while the vehicle may be at rest or in flight and also to secure the display of the advertising media while the airplane is flying normally 45 or inverted.

To that end the invention includes strips or sheets of suitable material indicated at S finished or so made as to embody and disclose any advertising subject matter that 50 may be desired. Preferably, a sheet of the advertising media is extended along a surface of the plane as between lateral guides 3—3 secured upon and extending along the longitudinal edges of the plane and also, 55 if desired, the advertising sheet or strip S

can be protected by a cover or casing portion 4 that may be of translucent, or transparent, or partly transparent material that will form a housing over the exposed surface of the advertising sheet so as to reduce 60 the friction of the wind or air upon the surface of the strip, and therefore permit it to be readily shifted as is desirable to expose different areas or parts of its length bearing, for instance, different advertising 65 matter.

The guide side strips and the covering sheet 4 may be suitably secured in place as by longitudinal cleats 6 riveted or otherwise secured to the edges of the covering 4 70 and resting upon the top of the marginal strips 3; the rivets 7 being shown, in the present case, to secure the parts in position.

In the present case I have shown the upper surface of the upper plane P of the airplane and the lower plane P' as provided with these shiftable strips or advertising sheets S, and the ends of the strips on each plane are respectively attached to winding drums 10 mounted upon suitable shafts 11 80 that are appropriately journaled in bearings at the corners of the plane, each of the shafts being provided at one, or the other, or both ends, if desired, with a means providing for the rotation of the shaft through power de- 85 rived from any suitable source.

In this case, an end of each of the drum shafts 11 is provided with a bevel gear 12 designed to mesh with a complementary driving gear 13 which is fast on the outer 90 end of a driving rod or shaft 14 appropriately mounted in bearings disposed along the edge of the plane as P, and the inner end of this shaft 14 is provided with a gear 15. 95

As shown in Fig. 2, the adjacent gears 15 on the ends of co-axial shafts 14 are designed to be alternately engaged with a gear 16 on the upper end of a shaft 17 which, in the present case, is mounted in journals 18, 100 Fig. 6, that are formed on or attached to an oscillating carrier or base member 19 which is mounted on the adjacent end of a shaft 20 which may be driven by power derived from any suitable source and not here 105 shown.

On the lower end of the shaft 17 there is secured a gear 17' and this is adapted to engage a master bevel gear 21 on the adjacent end of the driving shaft 20 so that the 110

shaft 17 may be driven in the desired direction.

Diametrically opposite to the shaft 17 there is another gear shaft 22 having a 5 pinion 21' at one end engaging the gear 21 and at its outer end a gear 23 adapted to be alternately meshed with either of the gears 15 disposed adjacent to the gear 23 and which are fixed on the contiguous ends 10 of the shafts 14 mounted on the lower plane P'. The shafts 14 on the lower plane are provided with driving gears 13 to engage with complementary pinions 12 on the respective shafts of the winding drums to 15 wind the movable advertising strip 20 on the lower plane.

Preferably, the winding drums at the ends of the planes are housed as by respective casings 26 which may be tapered at the front 20 ends 27 to reduce air resistance if desired.

Any suitable means may be utilized to selectively couple the mechanism of one of the strips to be shifted to the actuating means and, in this case, the bearing frame 25 19 may have attached to it the ends of a cable 28 lead in opposite directions over guide pulleys 29 and thence to a convenient position to enable the operator to draw on the chain or cable to draw, through it the 30 carrying frame 19 from one position to another. In this case the cable 28 is lead from the pulleys 29 around to a center pulley 30 and the cable may be provided with a handle 31 swinging on a suitable pivot 32, 35 so that movement of the handle in one direction pulls the gear selecting frame 19 in one direction and a pull on the handle 31 reversely will reverse the position of the gear selecting device.

40 Obviously the several advertising sheets or strips S may be provided with any desired advertising media as pictures, or signs, or may be advertised by the display of the name of the goods or trade-marks.

45 By providing a strip to be exposed along the top surface of the top plane and also another strip to be exposed along the bottom surface of the bottom plane it will be seen that these strips will be exposed whenever 50 the airplane is flying in a normal or in a reversed position.

Various changes may be made without departing from the spirit of my invention as claimed.

55 I claim:

1. In an advertising device for airplanes, the combination of display strips on its upper and lower wings, opposed drums at the ends of said wings for reversely winding 60 said strips, several actuating shafts operatively connected to one end of said drums, means for reversibly operating said drums through the medium of said several shafts,

said means comprising a drive shaft and master gear mounted thereon, an oscillating 65 frame pivotally mounted on said drive shaft, diametrically opposed shafts journaled on said oscillating frame and operatively connected at their inner ends to said master gear, and gears on the outer ends of 70 said shaft adapted to engage similar gears on the diagonally opposed ends of said drum actuating shafts, and manually operable means for causing selective engagement of 75 said last mentioned gears.

2. In combination with an airplane a drum at each end of the lower wing and the upper wing of the airplane, a strip secured at its ends to the drums at the ends of the lower wing, a strip secured at its ends to the drums at the ends of the upper wing, a bevel gear on the end of each drum shaft, two lower shafts, bevel gears on one end of said lower shafts meshing with the bevel 80 gears on drum shafts of the drums at the 85 ends of the lower wing, two upper shafts, bevel gears on one end of said upper shaft meshing with the bevel gears on the drum shafts of the drums at the ends of the upper wing, a bevel gear on the other end of each 90 of said shafts, an operating shaft, a frame fulcrumed on said operating shaft, two shafts journaled on said frame, a bevel gear on said operating shaft, bevel gears on the 95 inner end of said frame shafts meshing with the bevel gear on said operating shaft, and a bevel gear on the outer end of each frame shaft adapted alternately to mesh with the 100 gears respectively on the other end of said upper and lower shafts, when said frame is swung on its fulcrum, and means within reach of the aviator for swinging said frame.

3. In combination with an airplane a drum mounted at each end of a wing of said airplane, a strip extending over said wing and secured at its ends to said drums respectively, a bevel gear on each drum shaft, two wing shafts journaled on said wing, a bevel gear on one end of said wing shafts meshing with the bevel gears respectively on 105 said drum shaft, a bevel gear on the other end of each wing shaft, an operating shaft, a swinging frame fulcrumed on said operating shaft, a frame shaft journaled on said frame, a bevel gear on one end of said frame 110 shaft meshing with a bevel gear on said operating shaft, a bevel gear on the other end of said frame shaft for alternately meshing with the bevel gears on the other end of said wing shafts when said frame is 115 swung on its fulcrum, and means within reach of the aviator for swinging said frame on its fulcrum.

In testimony whereof I have signed my name to this specification.

RAYMOND K. BEVIER.
